Primary Examiner — Garth Rademaker*Assistant Examiner* — Laura H Yu(74) *Attorney, Agent, or Firm* — Leydig, Voit & Mayer, Ltd.(57) **CLAIM**

The ornamental design for a shoe, as shown and described.

DESCRIPTION

FIG. 1 is a lateral side view of a shoe showing my new design;

FIG. 2 is a front view thereof;

FIG. 3 is a medial side view thereof;

FIG. 4 is a rear view thereof;

FIG. 5 is a front-top perspective view thereof;

FIG. 6 is a bottom view thereof;

FIG. 7 is a front-lateral perspective view thereof; and,

FIG. 8 is a top view thereof.

The broken lines in the figures indicate portions of the shoe which form no part of the claimed design.

1 Claim, 8 Drawing Sheets(56)
